UNITED STATES PATENT OFFICE.

EDWIN E. CARLSON, OF CHESTER, PENNSYLVANIA.

MACHINE FOR WINDING WARP SHEETS.

Application filed February 5, 1925. Serial No. 6,978.

To all whom it may concern:

Be it known that I, EDWIN E. CARLSON, a citizen of the United States, residing at Chester, in the county of Delaware and State 5 of Pennsylvania, have invented certain new and useful Improvements in Machines for Winding Warp Sheets, of which the following is a specification.

My invention relates to winding machines 10 and is primarily designed for winding a binder thread upon the warp sheets which pass through the solutions employed for mercerizing yarns.

In mercerizing yarns, strands of yarn 15 have usually been grouped in rope form and a number of groups are concurrently led through the mercerizing solutions. A binding thread is wound spirally about each group to hold loose ends of threads which 20 may be broken in the mercerizing process to their group and prevent their clinging to and being wound around the rollers in the mercerizing mechanism. This requires a winding unit for each group. It is common 25 practice to provide mechanism capable of dealing with 24 groups at one operation and this involves providing 24 winding units. It has recently been found advantageous to group the strands side by side in 30 single ply, thereby forming a single warp sheet, and to bind the entire warp sheet with a single thread instead of binding each group separately.

The object of this invention is to provide 35 a machine for winding, or unwinding, warp sheets or other continuous sheets which may require such winding or unwinding.

I have illustrated my invention in connection with a single ply warp sheet but it 40 is adapted for use with continuous sheets of any type.

In the drawings,—

Figure 1 is a top plan view,

Figure 2 a side elevation,

Figure 3 a section on line 3—3 of Figure 2,

Figure 4 a section on line 4—4 of Figure 2,

Figure 5 a vertical section through one 50 form of spool carrier and spool,

Figure 6 an enlarged detail of a thread guide, and

Figure 7 a side elevation of another form 55 of spool with the thread guide.

In the drawings, 1 indicates the frame

of the machine, 2 the top or table, 3 cross bars, 4 a guide slot in the table through which the warp is led, 5 an oblong raceway of slot type encompassing the warp and having guide walls 6 and 7 within and upon which a spool-carrier 8 travels, 9 a drive sprocket and 10 a companion sprocket both disposed beneath the raceway, 11 a sprocket chain carried by the sprockets, encompassing the warp and having one of its links 12 60 detachably connected with a bearing block 13 adapted to support a spool-carrying sprocket 14, 15 a sprocket chain spaced from chain 11, disposed parallel thereto and in the same horizontal plane therewith and detachably fixed to a series of brackets 16 extending from the frame, 17 a sprocket wheel fixed to the spool spindle and meshing with chain 15, and 18 the spool which carries the binding thread 19. The spool is rotatable 65 upon its spindle 14 and is mounted upon spool-carrier 8. The spool-carrier, shown in detail in Figure 5, preferably consists of a sleeve 20 having an annular flange 21 and an enlarged part 22 and is threaded at its upper end to receive a stepped ball bearing 23 having annular flanges 24 and 25. The upper flange 25 carries a friction disk 26 upon which spool 18 is seated. The lower flange 70 supports the carrier upon the guide walls 6 and 7 of the raceway and flange 21 holds the carrier against upward displacement. Enlarged part 22 fits in the raceway slot and serves as a guide block for the spool carrier. 75

As the spool is seated upon friction disk 26, it is free to yield to any unusual strains.

A bracket 27, extending from the spool carrier, carries a standard 28 upon which a thread guide 29 is adjustably mounted. The 80 thread guide has two fixed members or eyes 30 and 31 extending therefrom and adapted to receive the binding thread 19. A shaft 32 is rockably mounted in the guide and carries a crank arm 33 which carries, at its free end, an electrical contact member 34, adapted to engage with a fixed contact member 35 extending from the guide, the contact member being in a normally open circuit including a switch which controls the motor. The guide is provided, between the stems of eyes 30 and 31 with a socket 36 and a block 37 fixed to shaft 32 is rockably seated in the socket. A pin 38 extends from the block in a plane between eyes 30 and 31. The binding thread 19 as it goes from the 85

90

95

100

105

110

spool to the warp sheet passes through the eyes and over pin 38. The tension of the thread normally holds the crank arm in raised position and contact member 34 out 5 of contact but, if the thread should break or the tension cease for any cause, the weight of the crank arm causes it to drop and close the circuit. Brushes 39 and 40 are mounted upon the spool carrier and are 10 connected by wires 41 and 42 with contact members 34 and 35 on the thread guide. The brushes are adapted to respectively engage conducting strips 43 and 43^a mounted upon insulating brackets 44 extending from 15 the frame. Strips 43 and 43^a are in circuit through a source of current 45 with a solenoid switch 46 which controls the motor 47 and engagement of contact members 34 and 35 closes the circuit through the solenoid 20 switch and stops the motor.

Drive sprocket 9 is mounted upon a shaft 48. A drive shaft 49 carries a spiral pinion 50 which meshes with a spiral gear 51 on shaft 48 and imparts motion to the shaft 25 and consequently to the drive sprocket and the movable chain.

The thread spool shown in Figures 2, 3 and 5 is in the form of a cylinder. In Figure 7 I have shown a cone-shaped spool 23^a 30 which is mounted in the same way as spool 23 but the standard 28^a is extended and the thread guide 29 is disposed above instead of alongside the spool.

In operation, the binding thread which 35 has been wound upon the spool, leads from the spool through eye 30, over pin 38 and through eye 31 to the warp sheet. Motion being imparted to drive sprocket 9 from drive shaft 49, sprocket chain 11, to which 40 spool carrier 8 is connected, is caused to travel continuously around the warp sheet thereby causing the spool carrier to travel in raceway 5 around the warp sheet. As the 45 spool and thread guide are mounted upon the spool carrier, they also travel around the warp sheet and cause the thread to be wound spirally thereon. As the spool travels rotary motion is imparted to its spindle 14 by sprocket wheel 17 meshing 50 with fixed chain 15. As the spool is seated upon friction disk 26 which is carried by a ball bearing member it is free to yield to undue strains. In case the binding thread 55 should break, crank arm 33, which has been held in raised position by the tension of the binding thread upon pin 38, will drop by gravity thereby bringing contacts 34 and 35 into engagement and closing the circuit 60 through solenoid switch 46 and thereby stopping the motor.

While I have described my invention as taking a particular form, it will be understood that the various parts may be changed without departing from the spirit thereof. 65 and hence I do not limit myself to the pre-

cise construction set forth, but consider that I am at liberty to make such changes and alterations as fairly come within the scope of the appended claims.

Having thus described my invention, what 70 I claim as new and desire to secure by Letters Patent is:—

1. In a machine for winding warp sheets, an oblong raceway encompassing the warp sheet a thread-carrying spool movably supported by the raceway, and means for causing the spool to travel about the raceway. 75

2. In a machine for winding warp sheets, an oblong raceway encompassing the warp sheet, an endless carrier encompassing the warp sheet, a spool-carrier movably supported by the raceway and attached to the endless carrier, and means for imparting motion to the endless carrier. 80

3. In a machine for winding warp sheets, an oblong raceway encompassing the warp sheet, an endless chain encompassing the warp sheet, a spool-carrier movably supported in the raceway and attached to the chain, and means for imparting motion to the chain. 85

4. In a machine for winding warp sheets, a frame including a table, a slot in the table adapted to receive the warp sheet, a slotted raceway encompassing the warp sheet, an endless chain encompassing the warp sheet and disposed beneath the raceway, a spool carrier attached to the chain and movably supported in the raceway, a spool carried thereby, and means for imparting motion to the chain. 95

5. In a machine for winding warp sheets, an oblong raceway encompassing the warp sheet, a thread carrying spool movably supported in the raceway, means for causing the spool to travel about the raceway, and means for rotating the spool. 105

6. In a machine for winding warp sheets, an endless carrier encompassing the warp sheet, a spool carrier attached thereto, a spool carried thereby, means for imparting rotation to the endless carrier, and means for rotating the spool. 110

7. In a machine for winding warp sheets, a frame, an endless carrier movably mounted thereon; an endless chain encompassing the warp sheet, and fixed to the frame; a spool-carrier attached to the endless carrier; a spindle mounted in the spool carrier; a spool rotatable upon the spindle and yieldingly seated on the spool-carrier; a sprocket wheel fixed to the spindle and meshing with the fixed chain, and means for imparting movement to the endless carrier. 115

8. In a machine for winding warp sheets, a sleeve rotatable upon the spindle; a member supported by the sleeve and fixed to the spindle; a friction disk carried by said member; a spool seated on the friction disk and rotatable upon the spindle; a sprocket wheel 120

fixed to the spindle and meshing with the fixed chain, and means for imparting motion to the endless chain.

9. In a machine for winding warp sheets, 5 an endless carrier encompassing the warp sheet; a spool-carrier attached thereto; a spool rotatably mounted thereon and carrying the binding thread; a motor for imparting motion to the endless carrier; a pair of 10 insulated conducting strips arranged adjacent the path of travel of the spool carrier and in circuit with a switch adapted to stop the motor; a pair of brushes on the spool carrier contacting with the conducting 15 strips; a thread guide carried by the spool carrier; a fixed and a movable contact member on the thread guide, and means on the thread guide whereby tension upon the thread normally holds the movable contact 20 member in open position and release of tension allows it to close and thereby close the switch circuit.
10. In a machine for winding warp sheets, 25 an endless carrier encompassing the warp sheet; a spool-carrier attached thereto; a spool rotatably mounted thereon and carrying the binding thread; a motor for imparting motion to the endless carrier; a pair of insulated conducting strips arranged adjacent 30 the path of travel of the spool-carrier and in circuit with a switch adapted to stop the motor; a pair of brushes on the spool-carrier contacting with the conducting strips; a thread guide carried by the spool- 35 carrier; a fixed contact member on the

thread guide; a shaft rockably mounted in the thread guide; a crank arm on the shaft; a contact member carried thereby, and a member extending from the crank arm and normally engaged by the thread whereby 40 tension upon the thread holds the contact member on the crank arm in open position, and release of tension allows it to close and thereby close the switch circuit.

11. In a machine for winding warp sheets, 45 an endless carrier encompassing the warp sheet; a spool carrier attached thereto, a spool rotatably mounted thereon and carrying the binding thread; a motor for imparting motion to the endless carrier; a pair of 50 insulated conducting strips arranged adjacent the path of travel of the spool carrier and in circuit with a switch adapted to stop the motor; a pair of brushes on the spool-carrier contacting with the conducting strips; a thread guide carried by the spool carrier; fixed eyes extending from the thread guide; a shaft rockably mounted in the thread guide; a crank upon the shaft; a contact members carried thereby, and a pin extending from the shaft between the fixed eyes and normally engaged by the thread whereby tension upon the thread holds the crank arm in raised position and release of tension allows it to drop and close 55 the switch circuit.

In testimony whereof I have signed my name to this specification.

EDWIN E. CARLSON.
